US00D756773S

(12) **United States Design Patent**
Brannock

(10) **Patent No.:** **US D756,773 S**
(45) **Date of Patent:** **** May 24, 2016**

(54) **LID WITH TEAR LINE**

(71) Applicant: **Harl-Bella Holdings, LLC**, San Juan Capistrano, CA (US)

AU 2007100927 A4 11/2007
CA 1236426 5/1988

(Continued)

(72) Inventor: **Samuel Lincoln Brannock**, San Juan Capistrano, CA (US)

OTHER PUBLICATIONS

(73) Assignee: **Harl-Bella Holdings, LLC**, San Juan Capistrano, CA (US)

Tree Hugger. Cuppow! Your Ticket to Fast Coffee in Cheap and Cheerful Mason Jars. Jan. 10, 2012 [online], [site visited Feb. 10, 2016]. Available from Internet, <URL: http://www.treehugger.com/green-home/cuppow-your-ticket-fast-coffee-cheap-and-cheerful-mason-jars.html>.*

(**) Term: **15 Years**

(Continued)

(21) Appl. No.: **29/526,890**

(22) Filed: **May 13, 2015**

Related U.S. Application Data

(63) Continuation-in-part of application No. 13/962,878, filed on Aug. 8, 2013, now Pat. No. 8,819,938.

Primary Examiner — Robert M Spear

Assistant Examiner — Darcey E Heflin

(74) *Attorney, Agent, or Firm* — Fish & Tsang LLP

(51) **LOC (10) Cl.** **09-07**

CLAIM

(52) **U.S. Cl.**

I claim the ornamental design for a lid with tear line, as shown and described.

USPC **D9/438; D9/447**

(58) **Field of Classification Search**

USPC D7/392.1; D9/434–436, 440, 443–445, D9/447, 452, 454, 499, 503, 741; 215/355; 220/705, 711, 713

CPC B65D 2543/0046; B65D 51/1677
See application file for complete search history.

DESCRIPTION

(Continued)

FIG. 1 is a top, rear, right side perspective view.

FIG. 2 is a front elevation view.

FIG. 3 is a rear elevation view.

FIG. 4 is a left side elevation view, the right side elevation being a mirror image

FIG. 5 is a top plan view.

FIG. 6 is a bottom plan view.

FIG. 7 is a cross section view taken in the direction of line 7-7 of FIG. 3; and,

FIG. 8 is an enlarged view of section 8 of FIG. 1.

In the drawings, the broken lines depict environmental subject matter only that forms no part of the claim.
